UNITED STATES PATENT OFFICE.

STEPHEN D. BAKER, OF NEW YORK, N. Y.

DESIGN FOR A WALL-RECEPΤΑCLE FOR SOAP AND OTHER TOILET ARTICLES.

50,291.

Specification for Design.

Patented Feb. 13, 1917.

Application filed November 25, 1916. Serial No. 133,500. Term of patent 14 years.

To all whom it may concern:

Be it known that I, STEPHEN D. BAKER, a citizen of the United States, residing at New York city, in the county of New York and State of New York, have invented a new, original, and ornamental Design for Wall-Receptacles for Soap and other Toilet Articles, of which the following is a specification, reference being had to the accompanying drawing, forming part thereof.

The figure is a perspective view of the receptacle taken from a point forward of the same, showing my new design.

I claim:

The ornamental design for a wall receptacle for soap and other toilet articles, substantially as shown.

In testimony whereof, I affix my signature.

STEPHEN D. BAKER.
